UNITED STATES PATENT OFFICE

EUGENE FULLER, OF ARCTIC, RHODE ISLAND, ASSIGNOR OF ONE-FIFTH TO JOSEPH R. BOURGEOIS, ONE-FIFTH TO THOMAS ROBERT, AND ONE-FIFTH TO RAYMOND GEOFFROY, OF ARCTIC, RHODE ISLAND.

WEIGHT-ACTUATED APPARATUS.

No. 823,521.

Specification of Letters Patent.

Patented June 19, 1906.

Application filed May 15, 1905. Serial No. 260,504.

To all whom it may concern:

Be it known that I, EUGENE FULLER, a citizen of the United States, residing at Arctic, town of Warwick, in the county of Kent 5 and State of Rhode Island, have invented new and useful Improvements in Weight-Actuated Apparatus, of which the following is a specification:

My invention pertains to apparatus in which the gravitation of a weight is utilized to actuate a bell-hammer, a whistle, or other signal or device; and it has for one of its objects to provide automatic means for raising the weight, so as to assure the same being always in position to actuate the device and this without interfering with the proper working of the device in the event that it is necessary for the weight to be raised and the device actuated synchronously.

Another object of the invention is the provision of means for automatically apprising a person in authority when the automatic weight-raising means fails to work, this to make known to such person that it is incumbent on him to raise the weight by hand in order to assure subsequent operation of the device by the gravitation of the weight.

The invention is designed more particularly for use in an electromechanical bell-striking apparatus such as employed in fire-alarm systems, and its novelty, utility, and practical advantages will be fully understood from the following description and claims when taken in connection with the accompanying drawings, forming part of this specification, in which—

Figure 1 is a perspective view of the apparatus constituting the present and preferred embodiment of my invention, the same being shown with the hammer in the position it assumes after the electromagnets are deenergized and before the hammer strikes the bell or other device on which the alarm is sounded. Fig. 2 is an enlarged detail perspective view of a portion of the apparatus, the rock-shaft *a* and its appurtenances being shown in the positions they occupy when the electromagnets are deenergized. Fig. 3 is an enlarged detail diagrammatic view illustrative of the means for giving an alarm in the event of the automatic weight-raising means failing to work. Fig. 4 is an enlarged

detail view illustrating the switch of the said means in one position. Fig. 5 is a similar view with said switch in another position. Fig. 6 is an enlarged detail side elevation illustrating the arrangement of the spring for cushioning the hammer and serving as a rest to normally hold the same away from the bell. Fig. 7 is a detail view of certain of the working parts of the apparatus. Fig. 8 is an enlarged detail view showing the manner in which the arm on the rock-shaft *a* is normally held against downward movement by the ledge on the armature.

Similar letters and numerals designate corresponding parts in all of the views of the drawings, referring to which—

A is a device to be struck, which device may be and preferably is a bell.

B is a hammer for striking the bell.

C is a spring for cushioning the hammer and normally retaining the same in a position away from the bell or device *A*.

D, a frame or stand which may be of any construction compatible with the purposes of my invention and is arranged adjacent to the hammer *B*, and *E* a transverse shaft journaled in the said frame or stand and bearing a drum *F*, a ratchet-wheel *G*, a spur-gear *H*, and a pallet-wheel *G'*. The drum *F*, ratchet-wheel *G*, and spur-gear *H* are fixed to the shaft *E*. The pallet-wheel *G'*, however, is loose on the shaft *E*, but is provided with ratchet-paws *I*, which are kept by springs in engagement with the teeth of the ratchet-wheel *G*. From this it follows that when drum *F* is turned in the direction indicated by arrow in Fig. 2 by the gravitation of the weight presently described the pallet-wheel *G'* will be caused to turn with the drum. When, however, the drum *F* is rotated with the ratchet-wheel *G* and the shaft *E* in the opposite direction, the pallet *G'* will remain idle.

J is an upright guide, *K* the weight, which is movable vertically at the side of said guide, and *L* a cable which is interposed between and connected to the drum *F* and the weight *J* and is passed over a suitable sheave (not shown) located in a position above the traverse of the weight. The weight *J* serves when it moves downward to rotate the drum *F* in the direction indicated by arrow in Fig. 2, and when the drum is rotated in the direc-

tion stated motion is transmitted from the same to the hammer B by means presently described.

a is a rock-shaft having an arm b, on which 5 is a lateral pin c. The said pin c is normally held against downward movement by a ledge d on an armature e when the said armature is attracted to and held against its complementary electromagnets f, which are designed to 10 be arranged in a normally closed fire-alarm circuit, and hence it will be noted that so long as the said circuit remains closed the shaft a will be held against rocking. When, however, the circuit in which the magnets f are ar- 15 ranged is broken and the said magnets are de- energized, the armature e is moved away from the magnets by a spring e⁰ or other means and the pin c is released from the ledge d. This enables a weight g on the shaft a and 20 a coiled spring g⁰, connected with the arm b, to forcibly rotate the said shaft a in the direction indicated by the arrow thereon in Fig. 2.

By reference to Fig. 7 it will be observed that when the shaft a is rocked in the direction indicated by arrow in Figs. 2 and 7 a dog 3 thereon raises an arm 4, which trips a catch 5, pressed by a spring 6, and permits the said catch to fly up. This allows the arms 7 and 8 to move with shaft 9 in the directions indicated by arrows and the arm 5^a to move downwardly, said arm 5^a being connected, through a rod 9^a, with the arm 10^a of the hammer B. After the catch 5 flies upward the gravitation of the weight J pulling on the drum F rotates 35 the pallet-wheel G' in the direction indicated by arrow, when said wheel acting first against one and then against the other of the pallets 11 and 12 rocks the arm 5^a down and up. At the end of each pallet there is a lateral pin 13, 40 which projects over a plate or guide 14, and at the end of each movement of the arm 5^a the said guide 14 causes one of the pallets to properly engage with a tooth of the wheel G' and releases the other pallet. On the forward movement of the arm 7 a pin 7^b thereon 45 engages an arm 15, fixed on the shaft a, with the result that the arm b and pin c are returned to the position shown in Figs. 7 and 8 relative to the armature e and the ledge d thereon, 50 ready for operation when there is another break in the circuit in which the magnets f are arranged. On the rearward movement of said arm 7 it slides into engagement with the catch 5 and enables the latter to hold the 55 arm 4, which is then in the position shown in Fig. 7. Said arm 4 is prevented from moving upwardly too far by the pin 16, disposed above it, as shown.

It will be apparent from the foregoing that 60 when the circuit in which the magnets f are arranged is broken the hammer B will first be moved rearwardly to the position shown in Fig. 1 and then forwardly against the bell or other device A to be struck; also, that subsequent to each blow of the hammer B the parts

will be secured in the position shown in Fig. 7, ready for operation when the magnets f are again deenergized.

I prefer to employ the mechanism shown in Fig. 7 and described in the foregoing for normally preventing operation of the weight-actuated drum F and for transmitting motion from the same to the hammer B. I do not desire, however, to be understood as confining myself to such mechanism, as any other suitable mechanism may be employed for the purpose without affecting my invention. 75

In addition to the appurtenances hereinbefore mentioned the shaft a is provided with an arm h, the purpose of which will be presently set forth.

L is a transverse shaft journaled in the frame or stand D and bearing a sprocket-gear M; N, a clutch member loosely mounted and movable endwise on the shaft L and backed by a spring N'; P, a spur-pinion fixed with respect to the clutch member N; Q, a spur-gear intermeshed with the pinion P; R, a spur-pinion fixed with respect to the gear Q and intermeshed with the spur-gear H' on the shaft E; S, an electromotor which *per se* may be of the ordinary construction or any other construction compatible with the purposes of my invention; T, a sprocket-belt connecting the gear M and the motor S, and U a clutch member complementary to the member P and fixed on the shaft L. When current is supplied to the motor S and the loose clutch member N is in engagement with the clutch member U, it will be observed that through the medium of the train of gearing described the drum F will be rotated in the direction opposite to that indicated by the large arrow in Fig. 2, and hence the weight J will be raised. Incident to the elevation of the weight J said weight is not adapted to actuate the hammer B, and from this it follows that in order to complete a fire-alarm the weight must be transferred—*i. e.*, connected to the hammer—so that the gravitation of the weight will operate to actuate the hammer. This is accomplished through the medium of the shaft a, the arm h of said shaft, a bell-crank lever V, fulcrumed on a bracket w, a cable X, connecting one arm of the said lever V, and the arm h of shaft a, a lever Y, fulcrumed on the frame or stand D and having a yoke i and also having a rod j, and a link k, connecting the arm of the lever V remote from the cable X and the lever Y. The yoke i of lever Y engages the loose clutch member N, and hence it will be observed that when the next fire-alarm is sent in and the electromagnets f are deenergized the shaft a will be forcibly rocked by the weight g in the direction indicated by the small arrow in Fig. 2, and hence, through the medium of the arm h, the cable X, the bell-crank lever V, the lever Y, and the yoke i of the latter, the clutch member N will be disengaged from the com- 115 120 125 130

plementary clutch member U. This will break the connection between the electromotor S and the weight J, and hence will enable the weight to gravitate and by such 5 gravitation forcibly impel the hammer B against the bell or other device A. Immediately after the shaft a is rocked by the weight g in the direction indicated by the small arrow in Fig. 2 said shaft and its appurtenances 10 return to their original positions ready for the next breaking of the fire-alarm circuit, and hence exert no power to hold the clutch member N out of engagement with the clutch member U. The finger j, however, performs 15 this latter function, for it will be seen that by reason of the said finger resting at the right of the hammer B, Fig. 1, the clutch member N is held away from the member U, with the result that the gravitation of the weight J is 20 exerted on the hammer B until said hammer is moved against the device A, when the finger j is released, and the spring N' operates to press the clutch member N against the member U, and thereby reestablishes winding of 25 the cable K on the drum F and elevation of the weight J. This operation is repeated during the sounding of an alarm or until the weight is in its uppermost position, as shown in Fig. 1. I prefer in practice to employ 30 such a motor and arrangement of gears that intermediate the blows of the hammer B against the device A the weight will be raised about twice the distance it falls to cause each blow of the hammer against the device A. 35 From this it follows that during the striking of an alarm the weight will be caused to move upwardly. This is materially advantageous, inasmuch as it assures the weight always having sufficient fall to strike an 40 alarm and renders it unnecessary for the traverse of the weight to be of undue length.

A', Fig. 3, is a source of electric energy with one pole of which the electromotor S is connected. B' is a post electrically connected with the other pole of the source of 45 electric energy. C' is a post connected electrically with the motor S, and D' is a switch hinged to the post C' and movable into and out of engagement with the post B'. Said 50 switch D' has a handle E' arranged in the path of an arm F' on the weight J, and hence when the said weight falls and its arm F' depresses the switch D', so as to close the power-circuit, the weight will be raised through the medium of the electromotor S and the driving connection described. If the weight J is 55 thus raised subsequent to the first blow of an alarm, the power of the weight will be transferred to the hammer B when the circuit on 60 the fire-alarm wires is broken for the next blow through the medium of the means before described in detail.

G' is an arm arranged on the upper portion of the weight J, and H' is a cable passed over 65 a sheave I' and connected at its upper end to

a suitable support and at its lower end to the switch-lever D'. The upper portion of the said cable H' is arranged to be engaged by the arm G' of the weight J when said weight reaches its uppermost position, as shown in Fig. 1, and hence it will be observed that when the weight reaches the said position it will operate, through the said cable H', to raise the lever D' up out of engagement with the post B' and will thereby break the power-circuit and stop the electromotor S and the parts connected therewith. 70

K', Fig. 3, is an electric bell which is electrically connected with a source of electric energy L' and a post M' shorter than the post B', and P' is a metallic conductor connected to the bell K' and one of the posts to which the switch-lever D' is hinged. In virtue of this construction it will be apparent that when the weight J arrives at a point one stroke or blow above that shown in Fig. 3 the arm F' will just engage with the handle E' of the switch-lever. On the next blow of the hammer B against the bell the weight J will drop and cause the switch-lever to make electric connection with the post B', and thereby complete the power-circuit and put the motor S in motion, so as to raise said weight J. If, however, any part of the machine is out of order and the electromotor 80 fails to raise the weight J at the time stated, the weight in making another drop will cause the switch-lever to move out of engagement with the post B' and into engagement with the shorter post m. This will complete the 85 alarm-circuit, and ringing of the bell K' will apprise a person in authority that the automatic weight-raising mechanism is out of order and that it is incumbent on him to make use of the crank M³ (shown in Fig. 1) and through the medium of the same raise the weight by hand. On the next blow of the hammer B the arm F' will slip past the handle E' of the electric switch, and the weight J will continue to fall. This additional fall of 90 the weight past the switch-lever D' is provided in order that no matter what happens the weight will travel downwardly a sufficient distance to complete the sounding of an alarm transmitted through the circuit in 95 which the electromagnets are arranged. When it is necessary to use the crank M³, the said crank is journaled in the standard M⁴ of the main frame and the pinion M⁵ of the crank is intermeshed with the spur-gear H. 100 If preferred, the said crank might be permanently mounted in the standard M⁴ and connected, as stated, with the spur-gear H without interfering with the automatic operation of the apparatus. 105

I have entered into a detailed description of the construction and relative arrangement of the parts embraced in the present and preferred embodiment of my invention in order to impart a definite understanding of the said 110

embodiment. I do not desire, however, to be understood as confining myself to the said specific construction and relative arrangement of parts, as such changes or modifications may be made in practice as fairly fall within the scope of my invention as claimed.

Having described my invention, what I claim, and desire to secure by Letters Patent, is—

- 10 1. The combination of a device to be actuated, an actuating-weight, means for raising the weight, means arranged when put in operation to interrupt the connection between the weight-raising means and the weight and transfer the power of the weight to the device to be actuated and reestablish the connection between the weight-raising means and the weight subsequent to the actuation of the device, and means for putting 15 said means in operation.
- 15 2. The combination of a device to be actuated, an actuating-weight, means for raising the weight, electromechanical means arranged when put in operation to interrupt the connection between the weight-raising means and the weight subsequent to the actuation of the device, and means for putting 20 said means in operation.
- 20 3. The combination of a device to be actuated, an actuating-weight, means for raising the weight, an electromagnet designed to be arranged in an electric circuit, and means controlled by the said electromagnet for interrupting the connection between the weight-raising means and the weight and 25 transferring the power of the weight to the device to be actuated and reestablishing the connection between the weight-raising means and the weight subsequent to the actuation of the device, and means for putting 30 said electromechanical means in operation.
- 30 4. The combination of a device to be actuated, an actuating-weight, means for raising the weight, an electromagnet designed to be arranged in an electric circuit, and means controlled by the said electromagnet for interrupting the connection between the weight-raising means and the weight and 35 transferring the power of the weight to the device to be actuated and reestablishing the connection between the weight-raising means and the weight subsequent to the actuation of the device.
- 40 5. The combination of a device to be actuated, an actuating-weight, means for raising the weight, an electromagnet designed to be arranged in an electric circuit, and means controlled by the said electromagnet for interrupting the connection between the weight-raising means and the weight and 45 transferring the power of the weight to the device to be actuated and reestablishing the connection between the weight-raising means and the weight subsequent to the actuation of the device; the said means comprising a finger movement of which in one direction is prevented by the device to be actuated when said device is in its normal position.
- 50 6. The combination of a device to be actuated, an actuating-weight, means for raising the weight, a connection intermediate said weight-raising means and the weight comprising a clutch, an electromagnet, means controlled by the said electromagnet for 55 interrupting the connection between the weight-raising means and the weight and transferring the power of the weight to the device to be actuated and reestablishing the connection between the weight-raising means and the weight subsequent to the actuation of the device; the said means comprising a finger, movement of which in one direction is 60 controlled by the said electromagnet for 65

transferring the power of the weight to the device to be actuated, and a lever connected with the said means and having an arm for moving one member of the clutch and also having means disposed at one side of the device to be actuated whereby said device in its normal position is enabled to prevent reestablishment of the connection between the weight-raising means and the weight.

6. The combination of a device to be actuated, an actuating-weight, a drum, means whereby motion is transmitted from the drum to the device when the drum is rotated in one direction and the device is left idle when the drum is rotated in the opposite direction, a cable passed over a sheave and connecting the drum and the weight, means for raising the weight, and electromechanical means for interrupting the connection between the weight-raising means and the weight and transferring the power of the weight to the device to be actuated and reestablishing the connection between the weight-raising means and the weight subsequent to the actuation of the device.

7. The combination of a device to be actuated, an actuating-weight, a drum, means whereby motion is transmitted from the drum to the device when the drum is rotated in one direction and the device is left idle when the drum is rotated in the opposite direction, a cable passed over a sheave and connecting the drum and the weight, means for raising the weight, a driving connection intermediate said means and the weight comprising a clutch, an electromagnet, an armature complementary thereto, means connected with said armature for controlling the transmission of motion from the drum to the device to be actuated, and a lever connected with the latter means and arranged to open the clutch and having a finger arranged to be held against movement in one direction by the actuating device when said device is in its normal position.

8. The combination of a device to be actuated, an actuating-weight, a connection between the weight and the device, an electro-motor, a connection between said motor and the weight for raising the latter by the former, a source of electric energy arranged in circuit with the motor, a switch also arranged in circuit with the motor and the source of electric energy, means on the weight and the switch for closing the switch when the weight moves downwardly and opening the switch when the weight moves upwardly, and means for interrupting the connection between the weight-raising means and the weight and transferring the power of the weight to the device to be actuated and reestablishing the connection between the weight-raising means and the weight subsequent to the actuation of the device; the said means comprising a finger, movement of which in one direction is 125 controlled by the said electromagnet for 130

prevented by the device to be actuated when the latter is in its retracted position.

9. The combination of a device to be actuated, an actuating-weight, a connection between the weight and the device, an electro-motor, a connection between said motor and the weight for raising the latter by the former, a source of electric energy arranged in circuit with the motor, a switch also arranged in circuit with the motor and the source of electric energy, means on the weight and the switch for closing the switch when the weight moves downwardly, and opening the switch when the weight moves upwardly, an auxiliary circuit including a source of electric energy and a signal, and means whereby the auxiliary circuit is completed when the weight moves downwardly subsequent to completing the first-mentioned circuit.

10. The combination of a device to be actuated, an actuating-weight, means for raising the weight, and means for interrupting the connection between the weight-raising means and the weight and transferring the power of the weight to the device to be actuated and reestablishing the connection between the weight-raising means and the weight subsequent to the actuation of the device; the said means comprising a finger movement of which in one direction is prevented by the device to be actuated when the latter is in its normal position.

11. The combination of a device to be actuated, an actuating-weight, means for raising the weight, a connection intermediate

5 said weight-raising means and the weight comprising a clutch, means for transferring the power of the weight to the device to be actuated, and a lever connected with the said means and having an arm for opening 40 the said clutch and also having a finger disposed at one side of the device to be actuated whereby the latter is enabled in its retracted position to prevent reestablishment of the connection between the weight-raising means 45 and the weight.

12. The combination of a device to be actuated, an actuating-weight, a drum, means whereby motion is transmitted from the drum to the device when the drum is rotated 50 in one direction and the device is left idle when the drum is rotated in the opposite direction, a cable connected with the drum and the weight, means for raising the weight, means arranged when put in operation to interrupt the connection between the weight-raising means and the weight and transfer the power of the weight to the device to be actuated and reestablish the connection between the weight-raising means and the 55 weight subsequent to the actuation of the device, and means for putting said means in operation.

In testimony whereof I have hereunto set my hand in presence of two subscribing witnesses.

EUGENE FULLER.
